UNITED STATES PATENT OFFICE.

GEORGE F. COUCHEY, OF VERMILION, OHIO, ASSIGNOR OF ONE-HALF TO A. G. SUMMERELL, OF VERMILION, OHIO.

RUST-RESISTANT LINER FOR AUTOMOBILE RIMS.

Application filed February 15, 1924. Serial No. 692,995.

To all whom it may concern:

Be it known that I, GEORGE F. COUCHEY, a citizen of the United States, and a resident of Vermilion, county of Erie, and State of Ohio, have invented a new and useful Improvement in Rust-Resistant Liners for Automobile Rims, of which the following is a specification, the principle of the invention being herein explained and the best mode in 10 which I have contemplated applying that principle, so as to distinguish it from other inventions.

The present invention relates to a liner covering for automobile rims and more particularly to a liner of non-rusting material adapted to protect the inner tube from contacting with the rim. Rubber in contact with iron rust deteriorates rapidly and the present device is adapted to be fixedly secured to the tire rim and is so formed as to cover the rim surface which can be contacted by the inner tube. It is particularly adapted for use in connection with small clincher types of rims such as are commonly used 20 on Ford cars as the clincher tires used on such rims are usually applied without any covering flaps or strips such as are often used on larger tires. To the accomplishment of the foregoing and related ends, said 30 invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Fig. 1 is a plan view of one form of liner; Fig. 2 is a fragmentary section through a rim showing the liner in place on a rim; Fig. 3 is a cross section of a liner, and Figs. 4 and 5 are views similar to Figs. 1 and 2 but showing a modified construction adaptable to split rims.

The present liner comprises a strap 1 of relatively thin rust-resisting material, preferably sheet tin zinc or the like. The strap should not only be of rust-proof or resistant material but also of a material relatively ductile so as to retain its shape when bent about a rim. As shown in Fig. 1 the liner 1 has a centrally located raised bead 2 throughout the major portion of its length

and at one end the strap has an aperture 3 while the other end is provided with a tongue 4. In mounting the liner on a rim, such as a clincher rim, the liner is narrow enough to pass between the bead rings 5 of the rim 6 and the aperture 3 is aligned with the valve stem hole 7 of the rim. The liner is bent about the rim and the tongue end lapped over the apertured end and the tongue 4 is forced through the aperture 3 and the valve stem hole 7 and is then bent backwardly as at 8 underneath the rim thus locking the liner securely in place.

The raised bead running circumferentially centrally of the liner is adapted to substantially fill the space between the tire beads 10, as best shown in Fig. 3, and thus aid in preventing pinching of the tube and like troubles. The tube is thus prevented from touching the iron or steel rim and is protected from the iron rust which causes tire trouble.

The form shown in Figs. 3 and 4 is adapted for use with transplit rims and in this form the liner 21 is provided with an elongated aperture 22 at one end, cut so as to form a bent-down tongue 23 which is inserted in the valve stem hole 24 and rebent along the under side of the rim as at 25. The other end of the liner is formed with an open-ended slot 27 adapted to receive the valve stem and align with the valve stem hole and the aperture 22. Thus, as the two ends of the rim are pulled apart in breaking the rim, the slotted end of liner 21 may pull off the valve stem. The tongue 23 may be eliminated, in which case the liner would tend to come off with the tube and it would be easily mounted and dismounted in this manner.

The present liner is simple in construction and easy to apply and is particularly adapted for use with clincher type rims and small sizes of clincher tires where no flap is used to protect the tube and in which it is difficult, if not almost impossible, to use the standard fabric flap, due to the method of applying the tire over the bead rings. By the use of a non-rusting or rust-resisting material the tube is entirely incased against touching the steel or iron rim and the iron rust has no opportunity to spoil the tube.

Other modes of applying the principle of my invention may be employed instead of

the one explained, change being made as regards the mechanism herein disclosed, provided the means stated by any of the following claims or the equivalent of such 5 stated means be employed.

I therefore particularly point out and distinctly claim as my invention:—

1. A liner for automobile rims comprising a strip of rust-resisting material adapted to be wrapped around the rim and provided with an aperture adapted to be aligned with the valve stem aperture of the rim, and a tongue adapted to extend through such valve stem aperture to secure 10 said liner to said rim.

2. A liner for automobile rims comprising a strip of rust-resisting material adapted to be wrapped around the rim and provided with an aperture at one end adapted 20 to be aligned with the valve stem aperture of the rim, and a tongue at the other end adapted to extend through such valve stem aperture to secure said liner to said rim.

3. A liner for automobile rims comprising a strip of rust-resisting material adapted to be wrapped around the rim and provided with an aperture at one end adapted to be aligned with the valve stem aperture of the rim, and a tongue at the other end adapted to extend through such valve stem 25 aperture to secure said liner to said rim, said strip having a centrally located raised bead extending throughout the major portion of its circumference.

4. A liner for automobile rims comprising a strap of rust-resisting, ductile metal adapted to be wrapped about the rim between the bead rings, one end of said strap having an aperture adapted to align with the valve stem aperture of the rim and the other end having a tongue adapted to pass through such aligned apertures in said liner and rim to lock said liner in place.

Signed by me, this 24th day of September, 1923.

GEORGE F. COUCHEY.
